UNITED STATES PATENT OFFICE.

CHARLES E. HEYER, OF CHICAGO, ILLINOIS, ASSIGNOR TO ARTHUR M. AND ALSON E. BARNHART, OF SAME PLACE.

DESIGN FOR A FONT OF PRINTING-TYPE.

SPECIFICATION forming part of Design No. 15,710, dated January 6, 1885.

Application filed September 15, 1884. Term of patent 14 years.

To all whom it may concern:

Be it known that I, CHARLES E. HEYER, a citizen of the United States, residing in the city of Chicago, county of Cook, and State of Illinois, have invented and produced a new and original Design for a Font of Printing-Types, of which the following is a specification, reference being had to the accompanying typographical illustration, forming a part hereof.

The character of the letter is ornamental, without shade or outline; and it consists of capitals, lower-case, figures, points, end ornament, catch-word "and," and three terminal lower-case letters, h m n.

The letter is a placid lapidary style of a conventional design, a curve ending with a disk or ball being a leading feature.

The letter has a somewhat square appearance in that the main strokes are more of a straight line, while the corners of some of the letters are rounded off.

The weight of the letter is nearly uniform in all parts of same.

A special feature of the letter is the extension of head or main ceriph, as shown on top of capitals J L U V and lower-case b d h i j k l r u v. Another similar feature is the extension of the diagonal ceriphs, as shown in lower-case a c s z and in figures 2 3 5 6 7 9. An entirely new feature of the letter is the horizontal bottom stroke of capital S, lower-case s, and dollar-mark, which extend beyond the main body of the letter. The center strokes of capitals A B H K P R and lower-case a b d k p q are disconnected from the main stroke of the letter, as is also the horizontal bottom stroke of capital D.

I claim—

The design for a font of printing-types without shade or outline, as described, and shown in the typographical illustration.

CHARLES E. HEYER.
